HUDSON MOTOR CAR COMPANY, OF DETROIT, MICHIGAN, A CORPORATION OF
MICHIGAN

STRIPING DEVICE

Substitute of application Serial No. 443,282, filed April 11, 1930. This application filed June 10, 1931.
Serial No. 543,436.

This invention relates to striping devices adapted especially for the purpose of rapidly applying paint or lacquer stripes to automobile bodies, and particularly along curved or marginal portions of belt line moldings or 5 beads, and window reveals.

An object of the invention is to provide an improved striping device which may be easily manipulated by the workman and capable of producing rapidly a relatively wide stripe having accurate and even marginal edges.

Another object of the invention is to provide a striping device particularly useful in 15 striping automobile bodies and having an improved applicator for striping along window reveals or moldings or beads.

Other objects of this invention will appear in the following description and appended claims, reference being had to the accompanying drawing forming a part of this specification wherein like reference characters designate corresponding parts in the several views.

Fig. 1 is a perspective view illustrating a striping device embodying the present invention as employed for forming a stripe along a molding or bead.

Fig. 2 is a central vertical section of the device.

Fig. 3 is a transverse vertical section.

Fig. 4 is a detail sectional view illustrating the manner of forming a stripe by means of the improved applicator.

Fig. 5 is a detail perspective view of the applicator.

Fig. 6 is a side view, partly in section, of one of the guides.

Before explaining in detail the present invention it is to be understood that the invention is not limited in its application to the details of construction and arrangement of parts illustrated in the accompanying drawing, since the invention is capable of other embodiments and of being practised or carried out in various ways. Also it is to be understood that the phraseology or terminology employed herein is for the purpose of description and not of limitation, and it is 45 not intended to limit the invention beyond 50

the terms of the several claims hereto appended as considered in view of the prior art and the requirements thereof.

Referring to Figs. 1 to 6 inclusive, the striping device herein shown by way of example comprises preferably a hollow supporting body 10 forming a reservoir 11 for containing the striping fluid, such as paint or lacquer. This reservoir is provided with a removable cap or closure 12 having a suitable air vent therein. The body 10 is provided with a forwardly projecting boss 13 which is tapped to receive a threaded plug 14 having a central bore within which is fitted a feed tube 15. The forward extension of the feed tube 15 forms a support for an applicator body 16 having a central bore to permit the applicator to be fitted onto the end of the tube. Within the forward end of the tube 15 is secured a plug 17 forming a valve seat 70 for a needle valve 18.

The striping device is grasped by the workman through the medium of a handle or stock 19, the upper portion 20 of which is suitably mounted on and secured to the body 10. The part 20 of the stock has a central opening 21, and through this opening and an opening 21a in the stock extends a trigger device 22. The upper end of the trigger is pivoted at 23 to the body 20. Intermediate 80 its ends within the opening 21 the trigger is engaged by a spool 24 which is spring pressed against the trigger by means of a compression spring 25. The tension of this spring may be adjusted by means of a screw plug 26 having a knurled head 26a. The spool 24 is fastened to the rear end of the needle valve 18. From this construction it will be seen that when the workman presses the trigger 22, the latter 90 retracts the spool 24 and thereby the needle valve 18, opening a passage through the valve member 17. The size of this opening, and hence the amount of paint adapted to flow from the reservoir to the applicator, may be governed by adjusting the member 26 relatively to the trigger member 22, resulting in varying the tension of spring 25. The member 26 is at the same time adapted to provide an adjustable stop for the trigger, limiting as desired the range of retraction there- 95 100

of so as to determine and regulate the flow of paint or lacquer to the applicator. Hence, after a predetermined relative adjustment of the parts, the workman will obtain a uniform stripe with the desired flow of paint by fully retracting the trigger device during the striping operation, and upon release thereof, the needle valve 18 will be shifted forwardly to close the passage, cutting off the flow of paint to the applicator.

The applicator body 16 is formed, in the present instance, with a pair of forwardly projecting pen nibs or blades 27 and 28. Leading from the chamber 16a, which is formed at the end of the feed tube 15, is a tube 29 which extends centrally between the nibs 27 and 28 to the extreme ends thereof. The forward portion 30 of the tube 29 is preferably flattened and also somewhat flared and joins the points of the pen nibs 27 and 28 as shown in Figs. 2 and 5. In this manner an applicator is formed in which the extreme ends of the pen nibs are joined by the flattened feed tube 30, and a narrow elongated orifice 31 for the discharge of paint or other fluid is formed between the nibs. Consequently, the end of the feed tube as well as the ends of the nibs form the applicator proper, which may be curved or concave in shape, as illustrated, so as to conform to the curved edge of a belt line molding or bead.

The foregoing construction of the applicator is important in providing a means for finishing off the edge of a stripe or painted area along the edge of a molding or bead M, see Fig. 1. As illustrated in this view the applicator is particularly adapted for filling in the unstriped portion 32 along the upper curved edge of the molding M at the junction of two areas having lacquer finishes of different colors or shades, producing a sharp and even border line between the color band on the molding M and the contrasting color of the panel L.

The applicator body 16 has a cylindrical bore which forms a snug fit over the feed tube 15, but permitting the applicator to be turned or rotated on the feed tube so as to locate the applicator nibs in different angular positions. In Fig. 1 the applicator nibs are in position to form a stripe along the area 32 at the upper edge of the molding, whereas in Fig. 4 the applicator nibs are turned at right angles or inverted to permit the blocking in of a stripe along the lower edge 32a of the molding M. In this manner the striping device may be used along the upper or lower edge of the molding without reversing the position of the device in the hand of the workman.

Supported by the applicator body 16 and the stock or handle 19 is an adjustable bar 33 which is constructed to carry devices for accurately positioning and guiding the striping gun during operation. Fitting over the

cylindrical end of the body 16 is a ring 34 carrying an adjusting screw 36 and nut 36a. The screw extends through a vertical slot 37 in the upper half of the bar 33, and the latter is held in fixed adjusted position by tightening the nut 36a. The lower half of the bar 33 is provided with a corresponding slot 37a and is adjustably connected to a sleeve 38 fitting over a projecting lug 38a secured to the lower end of the stock 19 by means of a set screw 39 extending through the slot 37a.

Adjustable vertically on the bar 33 is a sleeve 40 which is supported on the bar by means of an adjusting screw and nut 41 cooperating with the slot 37. The sleeve 40 carries a guide tube 42 within the bore of which extends a yielding guide member or bar 43. This member terminates in a guide ring 44 adapted to contact along the edge of the molding M for the purpose of guiding the striping device. The guide bar 43 is acted upon by a compression spring 45 and is connected to the tube or socket member 42 by a pin and slot connection 46.

Carried by the bar 33 is a second sleeve 47 which is adjustable vertically on the bar through the medium of the guide slot 37a by means of an adjusting screw and nut 48 cooperating with the slot. The sleeve 47 has a transverse bore through which extends a spindle 49 having a keyway 49a into which projects the end of a set screw 50 for locking the spindle in adjusted position within the sleeve 47. The forward end of the spindle 49 is bifurcated to receive a guide wheel 51 journaled therein. The wheel 51 has a peripheral tire of rubber or other friction material and is adapted to travel over the surface of the panel L beneath the pen nibs and in position between the lower part of the handle 19 and the panel so as to properly position the pen nibs at the required angle. The wheel 51 may be adjusted toward and from the handle stock 19 so as to properly determine the angle of the applicator and feed tube 15. Consequently, by means of the guide 44 and the wheel or roller 51 the guiding of the pen nibs over the surface being striped is nearly automatic, and the operation of the device is not dependent upon any particular skill of the workman.

We claim:

1. A striping device comprising a stock, a reservoir mounted thereon, an applicator body extending forwardly from said reservoir, a bar adjustably connected adjacent opposite ends to said body and stock, and a guide carried by said bar and adapted to engage the surface to be striped.
2. A striping device comprising a handle, a reservoir mounted thereon, an applicator body extending forwardly from said reservoir, a bar adjustably connected adjacent its opposite ends to said body and handle, and

a pair of guides adjustably carried by said bar.

3. A striping device comprising a stock, a reservoir mounted thereon, an applicator body extending forwardly from said reservoir, a bar adjustably connected adjacent its opposite ends to said body and stock, and a guide carried by said bar and adjustable separately in transverse directions.
- 10 4. A striping device comprising a reservoir for striping fluid, an applicator communicating with said reservoir, a handle extending downwardly beneath the plane of said applicator, a guide wheel adapted to travel over the surface to be striped, and means for adjustably supporting said wheel beneath said applicator and between said handle and said surface whereby to adjust the angular position of said applicator.

- 15 5. In a striping device, the combination of a stock, a reservoir mounted thereon, an applicator comprising a member terminating in a pair of spaced pen nibs, and a feed tube for striping fluid extending between said nibs, the outer end of said tube having a flattened orifice joining the outer extremities of the nibs and providing a pair of spaced walls forming with said nibs a stripe forming member, the end edges of said walls being

30 tween said nibs being concave.

In testimony whereof we affix our signatures.

RALPH Z. HOPKINS.
EARL SEGER.
